DIAMOND POWDER OR BORT FORMED DURING THE GRINDING OF DIAMONDS

Siegfried Roos, Amsterdam, Netherlands, assignor to Jozef Konkommer, Amsterdam, Netherlands

Application December 23, 1953, Serial No. 399,850

Claims priority, application Union of South Africa January 3, 1953

9 Claims. (Cl. 51—270)

The present invention relates to an apparatus for recovering bort formed during the grinding of diamond on a horizontal grinding mill, in which apparatus at least one substantially radially directed catching screen is so provided against the lower side of a hood arranged over the grinding disc as to be slightly spaced from and to be distributed in circumferential direction over the upper side of said disc, the arrangement being such that the air laden with bort, which whirls upwardly with great force, is intercepted, deflected and guided in another direction as a result of which it loses its capacity to carry the bort so that at least the larger part of said bort remains behind on the screens. Apparatus comprising a hood and catching screen is disclosed in my copending application Serial No. 277,126, filed March 18, 1952, now Patent No. 2,715,306, granted August 16, 1955.

According to this invention the hood rests with its circumferential edge on a sub-structure comprising a circular tray-shaped body having a central aperture in its bottom and a covering plate having a central aperture, said plate being located at some distance above said bottom and closely below the grinding disc and one or a plurality of blades or retaining screens provided between said bottom and said covering plate.

According to the invention this device can be received in a correspondingly shaped aperture in a table or like support, the grinding disc being driven via this aperture which registers with the central apertures in the sub-structure, by means of a vertical shaft passing through said apertures.

Such a device operates in the manner of a cyclone separator. When the grinding disc rotates the air below the hood is brought into turbulence and together with the bort which is formed therein by the grinding of one or more diamonds, it is hurled against the blades of the hood and via said blades and the upstanding wall of the tray of the substructure it is hurled against the blades of said substructure to be eventually discharged via the central apertures in the table and in the substructure.

By covering the blades of the hood and/or the upstanding wall of the tray and/or blades of the substructure at the side cooperating with the air with a bort-retaining coating, e. g. steel wool, gauze or the like provided with a sticky substance which retains the bort, it is possible to achieve that the air discharged only contains a minimum amount of bort. The openings in the hood through which the diamond holding means are passed, can be left open because the rotation of the grinding disc causes a current of air which is directed towards the sub-structure.

According to the invention this sub-structure can carry the blades in a detachable manner, which is desirable in order to enable the blades to be replaced by new ones when they have sufficiently performed their function of recovering bort.

According to another embodiment of the invention pairs of bort catching and retaining blades are secured to the bottom of the sub-structure, the blades of each

2

pair being curved inwardly and spaced from one another, and the pairs of blades being also spaced from one another, each blade extending from a point at some distance from the upstanding wall of the sub-structure towards the edge of the central aperture in the bottom of the sub-structure.

In both embodiments of the invention the hood may consist of plastic or another material having or capable of taking an electrostatic charge.

10 The drawings illustrate the invention by means of an embodiment of the apparatus.

Fig. 1 is a vertical section of an apparatus according to the invention on line I—I in Fig. 2;

Fig. 2 is a plan view thereof;

Fig. 3 shows a construction detail;

Fig. 4 is a vertical section on the line IV—IV in Fig. 5 of an apparatus of modified construction, the elements contained within the tray-shaped body of said apparatus being shown in elevation;

Fig. 5 shows a plan view of this apparatus, the hood being taken away and the horizontal grinding disc being partly broken away;

Fig. 6 is a plan view of the hood separately;

Fig. 7 shows a detail (one blade) of the hood.

25 In this embodiment a flat hood 3 is arranged over a horizontal grinding disc 1 which is secured on a vertical spindle 2, which spindle extends downwards from the grinding disc 1 and which can be driven by a source of power. The hood 3 is provided with four rectangular openings 4 which extend in radial direction and which are

30 uncovered and which serve for passing the diamond holding means therethrough. The hood 3 made e. g. from transparent plastic, has its inner side provided with e. g. plastic catching screens or blades 5, the under side of

35 which screens or blades 5 is located closely above the grinding disc. The hood 3 rests with its circumferential edge on a substructure comprising a circular tray-shaped body 6 having a central aperture 7 in its bottom and the upstanding wall of which is provided with a rim 8 which is bent at right angles outwards and subsequently upwards, which rim forms an accommodation for the edge of the hood 3.

40 At some distance above the bottom of the tray-shaped body 6 and parallel to said bottom a covering plate 10 provided with a central aperture 9 is arranged, which

45 plate has its upper side located closely below the grinding disc 1. In three places lips 11 are bent downwardly out of the covering plate 10; to each lip 11 a curved catching screen or blade 12 is detachably secured by means of a screw 13 which runs parallel to the covering plate 10. Each of these blades 12 is furthermore detachably connected with the bottom of the tray-shaped body by means of vertical screws 14; the blades, therefore, are the supports of the covering plate and keep this plate in its place because they are secured to the said bottom.

50 In addition to the above mentioned blades 12, to which the lips 11 are secured, there are blades 15 to which no lips are secured, but which otherwise are identical to the blades 12. Each blade 15 is located midway between two blades 12. The blades 12 and 15 have a recessed central portion, the recess or chamber being designated by the numeral 16. The screws 14 securing the blades to the bottom of the tray are screwed into the bottom of the chambers 16.

55 When the device is in operation, a current of air will be generated by the rotating disc 1. Bort originating from the grinding of diamonds on the grinding disc 1 and suspended in this current of air, will first be hurled against the catching screens 5, the concave sides of which are covered with a sticky substance, to which bort will adhere.

60 The air with any bort still suspended therein will sub-

sequently be hurled against the inner side of the up-standing wall of the tray-shaped body 6, which wall (in a manner not shown) is covered with gauze provided with a sticky bort-retaining substance, so that the air will again be stripped of some bort, whereupon the air will finally strike against the concave sides of the blades 12, 15 which are covered in a similar manner (not shown), the air being eventually discharged with as small as possible an amount of bort suspended therein, through the central aperture in the bottom of the tray-shaped body 6. The covering of the concave side of the blades 12, 15 may consist of steel wool provided with a sticky bort-retaining substance.

In the embodiment according to Figures 4-7 the main elements are identical to the main elements of the embodiment according to Figs. 1-3. A flat hood 3 is arranged over a horizontal grinding disc 1 which is secured on a vertical spindle 2, extending downwards from the grinding disc 1 and adapted to be power-driven.

The hood 3, which in this embodiment consists of two halves, is made of transparent plastic and is provided with four elongated openings 4 and two smaller elongated openings 17. All of said openings extend in radial direction and are uncovered; the openings 4 serve for passing the diamond holding means therethrough and for the entrance of air; the openings 17 serve also for the entrance of air between the adjacent openings 4. The hood 3 is provided internally with bort catching screens or blades 5, which are integral with the hood proper and which with their under side are located closely above the grinding disc 1.

The hood 3 rests with its circumferential edge on a sub-structure comprising a circular tray-shaped body 6 having a central aperture 7 in its bottom 18 and the up-standing wall of which is provided with a rim 8, forming an accommodation for the circumferential edge of the hood 3.

To the bottom 18 of the tray-shaped body 6 six pairs of bort catching and retaining blades 19, 20 are attached so as to be uniformly distributed over the circumference of said bottom. Each blade 19 has one end portion 21 circularly bent parallel or about parallel to the circular up-standing wall of the tray-shaped body 6 and spaced therefrom; the remaining portion 22 of each blade 19 is curved inwardly and extends up to the edge of the central aperture 7. Each blade 20 is uniformly curved throughout its length and extends from the free extremity of the circularly bent end portion 21 of a blade 19 up to the edge of the aperture 7.

The curvature of the blade 20 is the same as that of the portion 22 of the blade 19 and the blades 19 and 20 of a pair are spaced from one another. The six spaced sets of pairs of blades 19, 20 are encircled by a perforated, circular partition 23 spaced from the up-standing wall of the tray-shaped body 6. A covering plate 10 rests on the sets of blades 19, 20. This covering-plate is provided at its circumferential edge with three clips 24 adapted to slidably engage corresponding outwardly bent lips 25 attached to the outer side of the circularly bent end portions 21 of three of the blades 19.

The inner surface of the hood 3 the inner side of the up-standing wall of the tray-shaped body 6, the inner side of the bottom 18 of this body and all of the blades of the hood and of the sub-structure are covered by a bort-retaining means, e. g. a sticky substance.

The perforated partition 23 may also be coated with a bort-retaining means; this partition prevents small diamonds inadvertently fallen down through the openings 4 in the hood 3, from finding their way down through

the central aperture 7; they will now be received in the circular space 26 between the up-standing wall of the tray-shaped body 6 and the perforated partition. The operation of this embodiment will be clear after what has been

5 described in connection with Figs. 1-3.

I claim:

1. In apparatus for recovering bort formed during the grinding of diamonds on a grinding mill having a horizontal grinding disc, a sub-structure comprising a circular tray spaced below said disc and having a central aperture in its bottom, said tray having an up-standing wall at its periphery, a covering plate having a central aperture, said plate being located at some distance above the bottom of said tray and closely below said grinding disc and at least one catching screen provided between said bottom and said covering plate, and a hood arranged over the grinding disc and supported at its periphery by said up-standing wall of said tray, at least one substantially radially directed catching screen on the lower face of said hood, said screen being slightly spaced from, and distributed in a circumferential direction over, the upper face of said disc.

10 2. An apparatus according to claim 1, characterized in that the grinding disc is driven by means of a vertical shaft passing through said apertures.

15 3. An apparatus according to claim 1, characterized in that the catching screens of the sub-structure are detachably secured both to the bottom of the tray and to the covering plate.

20 4. An apparatus according to claim 3, characterized in that lips are bent downwardly out of the covering plate, to which lips the catching screens are detachably secured.

5. An apparatus according to claim 1, characterized in that selected surfaces of members comprising the hood, 25 the up-standing wall of the substructure and the various blades are coated by a bort-retaining means.

30 6. An apparatus according to claim 1, characterized in that the covering plate is integral with at least one bort catching and retaining blade.

40 7. An apparatus according to claim 1, characterized in that pairs of bort catching and retaining blades are secured to the bottom of said tray, the blades of each pair being curved inwardly and spaced from one another, and the pairs of blades being also spaced from one another, each blade extending from a point at some distance 45 from the up-standing wall of the sub-structure towards the edge of the central aperture in the bottom of the sub-structure.

8. An apparatus according to claim 7, characterized in that the pairs of blades are encircled by a perforated partition spaced from the up-standing wall of the sub-structure.

50 9. An apparatus according to claim 1, characterized in that the hood consists of plastic or another material having or capable of taking an electrostatic charge.
